DUAL PURPOSE BUCKLE

Joseph P. Schalet, Bronx, and Maurice D. Pollack,
Brooklyn, N. Y.

Application January 20, 1942, Serial No. 427,498

1 Claim. (Cl. 24—225)

This invention relates to buckles, and more particularly to buckles capable of functioning either as a buckle, or as an ornamental brooch.

The objects of our invention are, to provide a buckle, preferably in two parts each of which parts may be attached to one end of a belt or coat for securing the two ends together; to provide means for detachably interlocking the two parts to their respective ends; to provide means for adjustably interlocking the two parts to each other; and to provide means whereby both or either of the two parts may be separately attached for ornamental display purposes, such as for a brooch, etc.

We accomplish these and other objects and obtain our new results as will be apparent from the device described in the following specification particularly pointed out in the attached claim, and illustrated in the accompanying drawing in which:

Fig. 1 is a plan view of our buckle used on a belt.

Fig. 2 is a rear view of the same.

Fig. 3 is a side view of our buckle with all parts detached.

Fig. 4 is an additional side view illustrating one part of the buckle, used as a brooch.

In the drawing, reference numerals 10 and 11 designate the two body portions of our buckle, containing on their front surfaces ornamental mountings 12 and 13 respectively.

On the rear side of each, and extending normally therefrom, is soldered an extending ear, indicated as 14 and 15, containing threaded apertures 16 and 17. Each ear is positioned on the body portion at a point substantially adjacent to that edge, in proximity to the other body portion.

Body portion 10 is provided with a loop 18 which is rotatably mounted on the arm 19. The remaining end of the arm is threaded as at 21 for engagement with threaded aperture 16 of ear 14.

The body portion 11 is provided with a corresponding hook 22 having a threaded end 23 for engagement with threaded aperture 17 of ear 15.

The hook is designed to engage loop 18, interlocking the two body sections 10 and 11.

Because the interlocking means are detachable from their respective ears 14 and 15, they may be readily removed when not needed.

The two body sections are also provided with securing means for attaching the two sections to two ends of a belt, such as 24 and 25 respectively, shown in Fig. 1.

This may consist of pin clasps 26 and 27 shown in detail in Fig. 4, each having a body section 28, extending hinge section 29, hinge 30, hinged pin clasp 31, and pin clasp locking means 32, pref-

erably of the safety type and well known in the art.

Other well known types of securing means may be used.

5 By any of the foregoing types, we are able to instantly attach our device to two ends of a material for securing the two ends together. We are further enabled to lessen the distance between the two body portions, i. e., tighten the buckle, 10 by simply threading the threaded arms 19 and 23 into their respective threaded ears. Or we may loosen by unthreading or detach altogether when the hook and eye interlocking means are not needed and use the two body portions as ordinary brooches or apparel ornaments by use of 15 the securing means shown in Fig. 4. When the hook and eye portions are removed, the device loses its buckle appearance and does not interfere with its use as a brooch. This is illustrated in Fig. 4 where body portion 10 is used as a brooch attached to fabric 33.

Body portion 11 may individually be used as 20 a buckle by itself, the hook 22 being directly inserted into the apertures 34, in one end of the belt, 24, see Fig. 1, and securing means 27 used 25 to attach the buckle 10 to the remaining end 25 of the belt.

We have thus described our invention, but we 30 desire it understood that it is not confined to the particular forms or uses shown and described, the same being merely illustrative, and that the invention may be carried out in other ways without departing from the spirit of our invention, and therefore, we claim broadly the right to employ 35 all equivalent instrumentalities coming within the scope of the appended claim, and by means of which, objects of our invention are attained and new results accomplished, as it is obvious that the particular embodiments herein shown 40 and described are only some of the many that can be employed to attain these objects and accomplish these results.

What we claim and desire to secure by Letters 45 Patent, is as follows:

A buckle for attaching two pieces of fabric together, comprising two body sections, each lying in the plane of the fabric, and having a normally extending ear section provided with a threaded aperture, securing means for the body sections 50 for attaching each body section to a piece of the fabric; and interlocking means for separably attaching the two body sections to each other, said interlocking means terminating in a pair of bolt-like portions extending in the plane of the fabric, 55 and threaded for engagement with the threaded apertures of the body portions.

JOSEPH P. SCHALET.
MAURICE D. POLLACK.
